CLAIM

The ornamental design for a pet feeder, as shown and described.

DESCRIPTION

FIG. 1 is a front, bottom perspective view of a pet feeder, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the pet feeder, shown in a position of use with exemplary bowls.

The broken lines are shown for the purpose of illustrating both parts of the pet feeder as well as environmental subject matter of the exemplary bowls. None of the broken lines form part of the claimed design.
